UNITED STATES PATENT OFFICE.

JAMES L. CALHOUN AND WILLIAM H. CALHOUN, OF CHICAGO, ILLINOIS.

CARBON COPYING DEVICE.

SPECIFICATION forming part of Letters Patent No. 679,722, dated August 6, 1901.

Application filed December 3, 1900. Serial No. 38,424. (No model.)

To all whom it may concern:

Be it known that we, JAMES L. CALHOUN and WILLIAM H. CALHOUN, citizens of the United States, residing at Chicago, in the county of Cook and State of Illinois, have invented a new and useful Carbon Copying Device, of which the following is a specification.

This invention relates to a carbon copying device.

10 The object of the invention is to provide an apparatus which is simple in construction and efficient in operation for making and preserving carbon copies of way-bills, bills of lading, letters, and the like.

15 The invention consists substantially in the construction, combination, location, and arrangement of parts, all as will be more fully hereinafter set forth, as shown in the accompanying drawings, and finally pointed out in 20 the appended claims.

Referring to the accompanying drawings and to the various views and reference-signs appearing thereon, Figure 1 is a plan view of a carbon copy device embodying the principle of our invention. Fig. 2 is a bottom plan view of the same. Fig. 3 is a section on the line 3 3, Fig. 2, looking in the direction of the arrows. Fig. 4 is a transverse section on the line 4 4, Fig. 2, looking in the direction of 30 the arrows. Fig. 5 is a side view.

The same part is designated by the same reference-sign wherever it occurs throughout the several views.

Reference-sign A designates a suitable table 35 having a depressed seat B in the upper surface thereof. At the front and rear edges of said seat are provided passages or openings through the table, as indicated at C D, Fig. 4, the surface of the seat or depression B being beveled or cut away, as at E, as clearly shown. Similarly at the respective ends of the seat or depression B are provided openings or passages F G. (See Fig. 3.) Adjacent to the front and rear edges of the seat 40 or depression B and in convenient relation to the slits or openings C D, respectively, are provided hangers H. In hangers H are journaled rolls J K, one of said rolls having wound thereon a strip or sheet of suitable record-paper and constituting a supply-roll, the other of said rolls being adapted to receive such strip of record-paper and to wind

the same thereon from said supply-roll and constituting a receiving-roll for such strip.

The strip of record-paper is indicated by 55 reference-sign L, said strip being led from roll K through the slot or opening C, over the depressed seat B of table A, over the beveled surface E, through slit or opening D to and upon receiving-roll J. Any suitable 60 means may be provided for actuating the receiving-roll to effect a winding thereupon and from the supply-roll K of the strip of record-paper. A simple and convenient arrangement is shown, wherein a pinion M is mounted upon the end of roll J or upon the end of the shaft thereof, with which pinion engages a gear N, suitably mounted and supported by a bracket H. Pivotaly supported upon the axle of gear N is a hand-lever O, upon which 70 is mounted a pivoted pawl P, arranged to engage the gear N. Thus when lever O is swung in the direction indicated by the arrow in Fig. 5 and from the position thereof as shown in said Fig. 5 the pawl P, engaging gear N, 75 effects a rotative movement of said gear, thereby imparting to pinion M a rotation in a direction to effect a winding of the record sheet or strip upon roll J and from roll K. If desired and in order to regulate the extent of rotation of roll J, thereby regulating the amount or extent of the record-strip wound upon roll J at each actuation of lever O, a stop Q may be provided to limit the extent of movement of said lever O. This stop 80 may be made adjustable in any suitable or convenient manner—as, for instance, by mounting the same upon a slide R, operating in a groove in the surface of the table, as most clearly shown in Fig. 3—and, if desired, said stop may operate in connection with a graduated scale S. (See Fig. 1.) Thus by setting the stop Q at any desired point the lever O may be limited in its movement as desired to regulate the amount of record 85 strip or paper rolled from the supply-roll and wound upon the receiving-roll at each actuation of the lever.

In practice we prefer to arrange the brackets H on the under side of the table A, as shown, 100 and the rolls J K are arranged in parallel relation with respect to each other and with respect to the front and rear edges of the seat or depression B in the top surface of the table.

Suitably journaled in brackets H at the respective ends of the seat or depression B and extending parallel with such ends and transversely of the table A are rolls A' B', constituting, respectively, supply and receiving rolls for a strip or sheet of carbon C', said strip of carbon passing from the supply-roll, as A', through the slit or opening G at one end of the seat or depression B, thence over 10 the surface of said seat or depression and overlying the record sheet or strip L, thence through the opening or slit F at the opposite end of the sheet or depression, and thence to and upon the receiving-roll B'. Any suitable 15 or convenient means may be employed for effecting a proper travel of the carbon-strip when desired or necessary for presenting a fresh surface of the carbon. A simple construction is shown for accomplishing this re- 20 sult, wherein the roll B' is provided with a hand-crank D', (see Fig. 2,) by which said roll may be actuated whenever necessary or desired to effect an unreeling of the carbon-strip from the supply-roll and the winding of 25 the same upon the receiving-roll.

Of course it is obvious that any desired width of record and carbon strips or sheets may be employed and that the slits or openings D C will correspond in length to the 30 width of the record-strip L, while the slits or openings G F will correspond in length to the width of the carbon-strip C'. It is also ob- 35 vious that the widths of the record and carbon strips may be the same or of any desired relative proportion.

In practice we prefer to provide the edges of the depressed seat B with overlying protecting-strips, (indicated at E',) said protecting-strips forming guide-flanges for receiving 40 and guiding the edges of the carbon and record strips, thereby preventing buckling of such strips during the operation of the machine, and hence insuring a plain smooth writing-surface.

45 It may be desirable to provide means whereby it may be readily determined when it is necessary to present a new surface of the carbon. We have shown a simple and convenient arrangement for accomplishing this 50 purpose, wherein we provide a strip or sheet of glass (indicated at F') as a covering for the beveled surface E, said strip or sheet of glass being retained in place by the edge strips E' and by a retaining-strip G'. By 55 this arrangement the record-strip after being drawn from the position occupied thereby when receiving an impression from the carbon, will be exposed to view through the glass strip F', thereby disclosing the char- 60 acter of such impression and enabling the operator to determine when the carbon has been sufficiently worn to require the presentation of a new surface, such new surface being readily presented by manipulating the hand- 65 crank D' upon the carbon-receiving roll. If desired, the retaining-strip G' may be pro- vided with a projecting edge H', as clearly

shown in Fig. 4, which serves the double purpose of a guide for the edge of the carbon-strip C' and also a stop or gage for the original way-bill, bill of lading, or the like to be copied, thus enabling an operator to secure comparative uniformity.

Having thus described a construction and arrangement embodying the principles of our invention, we will now describe the purpose, function, and mode of operation thereof, supposing the parts to be initially in the respective positions thereof shown in the drawings.

A way-bill, bill of lading, original record-sheet, or the like (indicated at J', Fig. 1) is placed in position over the depression or seat B and over the carbon-strip C' and underlying record-strip L, it being understood that the 85 carbon surface of the carbon-strip is presented toward the upper surface of the underlying record-strip L. The desired entries are now made upon the sheet, way-bill, bill of lading, or the like J' with a pencil, stylus, or other 90 similar or suitable device. When the entry or writing has been completed, the original sheet, bill, or the like J' is removed and lever O is rocked, thereby winding the record-strip L upon its receiving-roll and carrying the 95 surface thereof (which has received a duplicate or copy of the entries made on the original sheet J' from the interposed carbon-strip) out of underlying position with reference to the carbon-strip, thereby presenting a fresh 100 surface of the record-strip to the carbon for the next succeeding entry or copy and expos- 105 ing the written surface through the glass strip F' to the inspection of the operator, and by suitably adjusting the stop Q the extent of movement of the record-strip will be regu- 110 lated, thereby economizing the record-strip to suit the extent of copying entry made thereon. The above operation is then repeated as often as desired and until the suc- 115 ceeding record-surfaces of the record-strip through the glass F' indicates the necessity for renewing the carbon surface, whereupon the hand-crank D' is actuated to move the carbon-strip, so as to present a fresh surface 120 thereof.

From the foregoing description it will be readily seen that we provide an exceedingly simple apparatus for accomplishing the desired results and wherein the work of making copies of way-bills, bills of lading, or other desired memoranda is greatly facilitated, thereby reducing the amount of labor required in large offices—such as railway-offices, express-offices, and the like—or in stores 125 or other places where it is desired to preserve copies of entries or other writings. The ma- 130 chine has few parts to get out of order, and the parts are simple in construction and arrangement and can be readily repaired or re- 135 newed when desired. The supply and receiving rolls for the record and carbon strips may be made readily removable from their bear- ings in brackets H for renewal purposes.

This removal may be effected in many different ways. A convenient and simple arrangement is to provide one of the hangers or brackets for each of the rolls with an inclined slot 5 or groove (indicated at K', Fig. 5) in a well-known manner, by which one end of said roll may be detached from its bearing by moving said roll laterally, whereupon said roll may be detached from its other bearing by an end-10 wise movement, as will be readily understood.

A device or machine such as above described can be constructed very cheaply and economically and requires no special skill or knowledge to manipulate or operate the 15 same.

Having now set forth the object and nature of our invention and a construction embodying the principles thereof, what we claim as new and useful and of our joint invention, 20 and desire to secure by Letters Patent of the United States, is—

1. In a carbon copying device, a table having a seat or depression in the upper surface thereof, and openings therethrough at the 25 sides and ends of the seat or depression in combination with receiving and supply rolls arranged in parallel relation with respect to each other and at opposite edges of said seat or depression, and adapted to receive there-30 on a record-strip, said record-strip intermediate said rolls passing over the surface of said depression or seat, and transversely-arranged receiving and supply rolls located adjacent to the ends of said depression or seat, and 35 adapted to receive a carbon-strip, said carbon-strip intermediate said rolls being arranged to operate over said record-strip, and means for actuating said rolls, as and for the purpose set forth.

2. In a carbon copying device, a table having an extended flat top surface and a seat or depression formed in a portion of such surface and openings formed through such table-top adjacent to the edges and ends of said 45 seat or depression, guides arranged along the edges and ends of said seat or depression, receiving and supply rolls arranged in parallel relation beneath the table-top and adjacent to the slots or openings at the edges of said 50 seat or depression and adapted to receive a record-strip, said record-strip intermediate said rolls operating through said edge slots or openings and over the surface of said depression or seat and having its edges guided 55 by the end guides, and transversely-arranged receiving and supply rolls arranged adjacent to the slots or openings at the ends of said seat or depression adapted to receive a carbon-strip, said carbon-strip intermediate said 60 rolls operating over the surface of said depression or seat and said record-strip, the edges thereof being guided in said edge guides, and means for actuating said rolls, as and for the purpose set forth.

3. In a carbon copying device, a table hav- 65 ing a depression or seat in the upper surface thereof and having slits or openings therethrough at the ends and sides, respectively, of said seat or depression, in combination with means for moving a record-strip through 70 the slits or openings and over the surface of said seat or depression, and means for moving an overlying carbon-strip through the slits or openings at the ends and over the surface of said seat or depression, the side walls of said 75 seat or depression forming a limit-stop for a loose way-bill or the like, whereby succeeding bills or the like are always brought into the same relation with respect to the carbon and record strips, as and for the purpose set 80 forth.

4. In a carbon copying device, a table having a seat or depression in the surface thereof, and a beveled surface at one edge of said seat or depression, and having slits or openings 85 therethrough at the edges and ends of said seat or depression, means for moving a record-strip through the slit or opening at one edge of said seat or depression and over the surface of said seat or depression and through the 90 slit or opening at the other edge of said seat or depression and over said beveled surface, and means for moving an overlying carbon-strip through the slits or openings at the ends of said seat or depression, and a transparent 95 top or cover arranged over the beveled surface and underneath which the record-strip passes after receiving an inscription, as and for the purpose set forth.

5. In a carbon copying device, the combina- 100 tion of a table having an extended plain flat top provided with a seat or depression therein, said seat or depression provided with a beveled surface at one edge thereof, said table having slits or openings therethrough at 105 the edges and ends, respectively, of said seat or depression, receiving and supply rolls arranged in parallel relation and adapted to receive a record-strip, said record-strip intermediate said rolls passing through the slits or 110 openings in the edges of said seat or depression and over the surface thereof and said beveled surface, means for moving an overlying carbon-strip through the slits at the ends of said seat or depression, and a glass 115 sheet or strip overlying said beveled surface and arranged at one side of the path of said carbon-strip and beyond the edge of said seat or depression, as and for the purpose set forth.

In witness whereof we have hereunto set 120 our hands, this 28th day of November, 1900, in the presence of the subscribing witnesses.

JAMES L. CALHOUN.
WILLIAM H. CALHOUN.
